UNITED STATES PATENT OFFICE.

CHARLES W. GLIDDEN, OF LYNN, ASSIGNOR TO THE MCKAY AND BIGELOW HEELING MACHINE ASSOCIATION, OF BOSTON, MASSACHUSETTS, JAMES W. BROOKS, TRUSTEE.

LAST.

SPECIFICATION forming part of Letters Patent No. 278,426, dated May 29, 1883.

Application filed March 22, 1883. (No model.)

To all whom it may concern:

Be it known that I, CHARLES W. GLIDDEN, of Lynn, county of Essex, State of Massachusetts, have invented an Improvement in Lasts, 5 of which the following description, in connection with the accompanying drawings, is a specification, like letters on the drawings representing like parts.

My invention relating to lasts is embodied in 10 a last of the kind that is used for holding boots or shoes while the heels are being applied thereto or trimmed. Lasts of this kind commonly consist of a heel portion connected by a shank or stem with a toe portion, which has 15 commonly been pivoted to the said shank, to enable the last to more readily be inserted in the boots or shoes to be operated upon.

As heretofore constructed the pivotal movement of the toe portion of the last on the shank 20 of the last has been in a vertical plane, and the pivotal point has commonly been either at the end of the toe portion of the last adjoining the shank or at some distance below the surface that rests in contact with the sole of the 25 boot or shoe, and the movement is not sufficient to properly accommodate the last to shoes of different style or shape.

The present invention consists in a last having the toe-piece both pivoted and swiveled 30 thereon, so as to rock in a vertical plane, and also to turn laterally on an upright axis, to thereby accommodate the last to shoes having more or less spring and a greater or less deviation from symmetry of the sole in what are 35 known as "right and left" boots or shoes. The toe-piece also has an adjustment vertically with relation to the heel, to further accommodate the last to shoes of various spring.

Figure 1 is a side elevation, partially in longitudinal section, of a last embodying this invention; and Fig. 2, a transverse section thereof on line *xx*.

The heel-piece *a*, of usual or suitable construction, has the shank *b* connected therewith 45 in any usual manner. The forward or toe end of the said shank, shown as turned upward, is provided with a socket, 2, shown in this instance as screw-threaded and adapted to re-

ceive the threaded stem *c* of the pivot-piece *d*, which is extended upward between two lugs, *e*, 50 of the toe-piece *f* of the last. The said toe-piece *f*, lugs *e*, and pivot-piece *d* are bored transversely near the sole-receiving portion of the said toe-piece, to receive the pivot-pin or spindle *i*, upon which the said toe-piece has a rocking movement in a vertical plane. By locating the pivot nearer the middle of the toe-piece than its end, as heretofore common, and nearer its sole-supporting face than common, the said toe-piece will more readily accommodate itself 55 to the shoe than when pivoted near its end. It will be seen that the said toe-piece, together with the pivot-piece *d*, is free to turn or swivel laterally within the socket 2 of the shank *b*, and that by rotating the said toe-piece the 60 swivel-stem will move longitudinally, and the toe-piece may thus be raised or lowered relatively to the heel-piece *a*. By the lateral swiveling movement of the toe-piece in the socket 2 and the rocking movement of the toe-piece 65 on its pivot *i*, and the vertical adjustment of the said toe-piece relative to the heel portion *a*, the last may be made to receive and properly fit and support right and left boots or shoes of various different shapes without stretching 70 or distorting the same, the boot or shoe being easily drawn into place upon the said last.

I claim—

1. In a last, the heel portion and shank, combined with the toe-piece, having its horizontal pivot elevated above the surface of the heel portion, substantially as described.

2. The heel-piece and shank, combined with the vertically-adjustable toe-piece, substantially as described.

3. The heel-piece and shank, combined with the toe-piece, having both ends free to rock vertically about a horizontal pivot located above the said shank, substantially as described.

4. The combination of the heel portion and shank of a last with the toe-piece having its pivot nearer the middle of its length than its ends, the said pivot being located near the face of the sole-support, substantially as shown and described, and for the purposes set forth.

5. The heel portion and shank, combined with the toe portion pivoted and swiveled thereon, as described, whereby it is free to rock in a vertical plane or turn laterally to accommodate the last to shoes of different shape, substantially as set forth.
6. The heel portion, shank, and toe-piece, combined with the pivot-piece for the said toe-piece, swiveled and longitudinally movable in the said shank, substantially as described.

In testimony whereof I have signed my name to this specification in the presence of two subscribing witnesses.

CHARLES W. GLIDDEN.
